UNITED STATES PATENT OFFICE.

ALBERT J. MILLIGAN, OF SAN FRANCISCO, CALIFORNIA.

GAS APPLIANCE.

Application filed November 24, 1926. Serial No. 150,469.

This invention relates to improvements in gas appliances and more particularly to gas saving attachments to gas burners. Among the objects of the invention are to insure efficient use of the gas burner by automatically shutting off the gas supply when the burner is not in use, and to automatically turn on the gas and ignite the burner when heat is desired, independent of the conventional manual control and regulation of the gas supply to the burner. Another object is to conserve the time of cooks, more especially in restaurants, where much time is lost in regulating the gas for different kinds of fry orders, requiring different volumes of heat. With this invention applied to several burners, the burner adjusted to the desired volume of heat is chosen and the utensil set upon it without further attention until it is done. One of the advantages of this invention is lowering the temperature in small kitchens during the rush hour, since only those burners actually cooking are ignited. It is an established fact that few cooks will turn off a burner after they are through with it, accounting for wasted heat, often as high as fifty per cent over that required in actual cooking.

Other objects and advantages will appear as this description progresses.

In this specification and the annexed drawings the invention is illustrated in the form considered the best, but it is to be understood that it is not limited to such form, because it may be embodied in other forms, and it is also to be understood that in and by the claims following the description it is desired to cover the invention in whatsoever form it may be embodied.

In the accompanying one sheet of drawings; Figure 1 is a side elevation of a gas stove, partly in vertical section, having this invention applied to the burner thereof. Figure 2 is a plan view from above of the same, the stove being omitted. Figure 3 is an enlarged fragmentary detail in horizontal section, of the gas control of a conventional burner having this invention combined therewith. Figure 4 is a similar view of the gas control parts, showing a modified form wherein the pilot tube is utilized in the automatic operation of the control valve.

In detail the construction illustrated in the drawings, see Figure 1, comprises the stove top 1 supported on the legs 2 and having the open grids 3. The burner comprising the mixing chamber 4, the throat 5 and the aspirator 6 is mounted beneath the grids on the support 7 at the rear and at the front on the service cock 8 that is screwed into the service pipe 9. This combination comprises the conventional "gas shelf" or "hot plate" with modifications to fit any type to which this invention is applicable, with suitable adjustment as provided for.

The automatic gas control element, see Figure 3, comprises the nipple 10 centrally drilled to slip onto the end 11 of the manual gas service cock 8. To compensate for slight variations that may exist in the diameter of the end 11; the nipple is internally provided with the compressible gasket 12 composed of any suitable asbestos compound adapted to give the necessary elasticity, with heat resisting qualities. This nipple extends through a central opening in the head 13 of the diaphragm across the face of the aspirator 6. The inner end of the nipple is transversely drilled to receive the control plug valve 14, ground therein to make a gas tight fit. The end of this plug is threaded to receive the screw 15 to force the washer 16 against the side of the nipple to hold the plug in proper operative position without undue friction, so that this plug is freely operable without gas leakage. The opposite end of the plug is drilled to receive the transverse pin 17 fixed therein. The head 13 is provided with a lateral gap to pass the projecting head of the plug 14.

With the plug in the "open" position, that is with the pin 17 raised, as in Figure 1, the central hole 19 is drilled through the end of the nipple 10 and the plug 14, to meet the gas chamber 20, between the end 11 of the cock 8 and the bottom of the hole extending into the nipple. This hole 19 is arranged in axial alignment with the axis of the throat 5 of the burner and is within the aspirator 6. The location of the control valve 14 within the aspirator has several advantages, therein it is protected from accumulations of grease, spilled food stuff and other matter liable to interfere with its free and easy working. Its location also provides for the easy installation of this invention to stoves having a limited distance available between the cock 8 and the aspirator 6, without alteration of the stove and burner parts, beyond merely cutting a gap to pass the valve 14 through the head 13.

The pin 17 is bent at right angles outside the aspirator 6 and pivotally extends through

the socket formed by the spiral coil 21, the end 22 of which extends forward to form the lever 22. The opposite end 23 extends rearwardly, terminating in a bent eye to receive the counter-balancing weight 24. The lever 22 extends forward about the conventional length of the burner throat 5 and is bent back upon itself at 25 forming the extension 26 parallel with the lever 22, and both are flattened under a die to form a flat surface to receive the bent ends 27—27 of the trip. These bent ends form a sliding friction clamp, engaging the surfaces of the levers 22 and 26 for the purpose of longitudinally adjusting the trip on the lever 22.

The trip 28 preferably consists of a single length of wire bent back upon itself, one extension being bent laterally at 29, terminating in the clamp end 27, the opposite end being bent at 30 and 31 to form a loop, the parallel extensions 32 and 33 of which rest upon the top of the said throat of the burner, acting as a fulcrum for the lever 22. The extension 32 terminates in the other clamp end 27.

The weight 24 acts as a counter-balance for the weight of the lever 22 and the trip 28, to hold the plug valve 14 normally in the closed position by depressing the pin 17, the lever trip 28 fulcruming on the extension 32—33 of the loop.

The pilot light for igniting the burner, comprises the small tube 34 having its inner end driven tightly into the lug 35 on the side of the nipple 10, and having a by-pass 36 leading into the chamber 20. The opposite end of the tube extends forward and is directed across the top of the burner 4.

This invention operates substantially as follows: The utensil X is placed in position 40 on top of the grids 3. The service cock 8 is then turned on manually and the gas ignited at the burner in the usual manner, this also ignites the pilot light. When the utensil X is lifted, the trip 28 rises, under the influence 45 of the counterweight 24, this depresses the end of the lever 22 carrying the pin 17 downward, causing it to turn the plug 14 into the "off" position and arrest the flow of gas through the passage 19, without shutting off 50 the pilot light. When a utensil is again placed in position, the trip is depressed and the reverse operation of the mechanisms controlling the plug 14 causes it to return to the "on" position again, admitting gas to the 55 burner, which ignites from the pilot, the flow of gas being automatically controlled by the manipulation of the utensil X. The manual control of the burner through the cock 8 is not interfered with by the combination of this 60 invention. To determine the "on" and "off" positions of the control valve 14, it is provided with the annular flange 37, having a segmental gap therein engaging the pin 38 fixed in the side of the nipple 10.

65 Referring to Figure 4, the construction and

operation of the other mechanisms are unchanged excepting that the plug 14 is provided with an axial by-pass at x^{15} communicating with the hollow pin at x^{17} driven into the plug x^{14} to meet it. The end of the pin 70 x^{17} is bent and extends into the bent end x^{21} of the lever x^{22} , that is flattened at x^{26} to receive the clamped ends 27—27 of the trip 28. The counter-weight 24 is fixed directly to the end x^{21} . The transverse gate or by-pass 75 through the plug x^{14} , co-operating with the hole x^{19} is opened at its inner end into the larger opening x^{39} communicating with the chamber 20, whereby the gas is free at all times that the valve 8 is open, to flow through 80 the hole x^{39} , the by-pass x^{18} , the pin x^{17} and the lever x^{22} pivoted thereon, and open at the end 40 directed toward the top of the burner 4, all these tubular parts are adapted to act as a pilot tube for igniting the burner. The 85 mode of operation in controlling the valve x^{14} by the operation of the trip 28, is the same in the modification shown in Figure 4, as shown and described as to Figure 1. The advantage of the modification is the elimination 90 of the secondary pilot tube by incorporating it within the operating mechanism of the control valve x^{14} .

Having thus described this invention what I claim and desire to secure by Letters Pat- 95 ent is:

1. In combination with a gas stove adapted to support a utensil; a gas burner; a rotary control valve having a pin projecting at right angles therefrom; a counterbalanced control lever pivoted on said pin and within its length resting on the throat of said burner the latter affording a fulcrum therefor; and a trip 100 fixed to said control arm and adapted to engage said utensil.

2. In combination with a gas stove adapted to support a utensil and having a gas burner; a rotary control valve on said burner having a pin projecting at right angles therefrom; a control lever pivoted on said pin and extending along the throat of said burner and having a slideable part resting on said throat the latter affording a supporting fulcrum therefor, and having a trip adapted to engage said utensil. 110

3. In combination with a gas stove adapted to support a utensil and having a gas burner; and a service valve; a nipple interposed between said service valve and said burner; a rotary control valve in said nipple having a valve control pin projecting at right angles therefrom; a wire lever having a transverse coil intermediate its ends and pivoted on said pin one end of said lever extending forward of said pin and bent back upon itself to form a loop; a counter-weight on the other end of said lever; a wire trip slidably engaging said loop resting on and fulcrumed on the throat of said burner and having an extension 120 adapted to engage said utensil. 130

4. In combination with a gas stove adapted to support a utensil and having a gas burner and a rotary control valve having an angular pin projecting at right angles therefrom; a
5 wire control lever having a coiled end pivotally engaging said pin and its other end flattened and bent back upon itself to form a loop; a wire trip adapted to engage said uten-

sil and bent back upon itself and having a laterally looped extension adapted to rest on 10 and fulcrum on the throat of said burner and its opposite ends bent back and clamped to the loop of said control lever

In testimony whereof I have hereunto affixed my signature.

ALBERT J. MILLIGAN.
